UNITED STATES PATENT OFFICE.

BENJAMIN FARNESS, OF DE FOREST, WISCONSIN.

FORM FOR HOLLOW CONCRETE WALLS.

1,401,898.

Specification of Letters Patent. Patented Dec. 27, 1921.

Application filed December 14, 1920. Serial No. 430,666.

To all whom it may concern:

Be it known that I, BENJAMIN FARNESS, of De Forest, in the county of Dane and State of Wisconsin, have invented certain 5 new and useful Improvements in Forms for Hollow Concrete Walls; and I do hereby declare the following to be a full, clear, and exact description of the invention, such as will enable others skilled in the art to which 10 it appertains to make and use the same.

My invention relates to the construction of concrete walls for houses and other buildings and particularly to hollow concrete walls, the object of my invention being to 15 provide a simple and highly efficient form or mold for such construction work, the form embodying improved and simple features rendering it capable of being readily removed after the cement has set.

20 A further object of the invention is to provide in a mold of the type stated improved means for the formation of a window or other opening in the wall which obviates the necessity of using a finishing casing on 25 either the inside or outside of the building.

In the drawings, Figure 1 is a horizontal sectional view of a portion of my improved form, the mold members for the window opening being shown about centrally of the 30 portion at the left. Fig. 2 is a vertical sectional view on the line 2—2, Fig. 1. Fig. 3 is a horizontal sectional view on line 3—3, Fig. 2. Fig. 4 shows a portion of the mold members in detached arrangement, the strips 35 being vertically placed instead of horizontally for the sake of clearness.

As shown in the drawings, I utilize two mold sets, A and B, spaced apart to form the hollow C of the wall, each set including 40 a series of outer or exposed members 1 and a series of inner or concealed members 2. The outer members 1 are formed of vertically disposed boards adapted to be arranged side to side and provided with bracing uprights 3 at each side of the members 1, complementary uprights being gripped by U-shaped clamps 4 through each of which is passed an L-shaped locking bolt 5. The inner end of this bolt is screw threaded and 45 takes in a threaded opening of a plate 6

adjustable on and supported by a strip 7. So that adjacent boards 1 may snugly abut these boards, the uprights 3 are transversely grooved as at 8 to accommodate the bolts 5. Angular continuations of the outer members 55 1 are readily provided for by braces 9 bolted or otherwise connected with the boards 1.

The inner members 2 of each set A and B are formed of a series of vertically disposed boards 12 to some of which are secured sheet metal plates 13, the width of these plates being greater than the width of the boards to which they are attached so as to lap the space between the sides of adjacent boards, and such plates have openings 60 14 through which the bolts 5 pass for engagement with their locking plates 6. As before stated these plates are carried by strips 7. There are a number of these strips placed end to end and extending horizontally, the adjacent ends having a lap joint fit, as indicated at 15. In order to secure the necessary spacing between the outer members 1 and the inner members 2 to give proper thickness to the concrete I employ 65 wooden blocks 16 at the points where the bolts 5 are used, such bolts remaining embedded in the concrete when the forms are taken down. Because of their smallness these blocks do not in any way detract from 70 the effectiveness of the wall. I preferably arrange the strips 7 which lock the boards of the outer mold set in juxtaposition to the strips 7 of the inner mold set so that these elements form a spacing means between the 75 two mold sets A and B, thus securing the desired hollow space.

In the formation of the wall about openings for windows and the like difficulty has frequently been experienced because of inability to use the mold parts as adopted for uninterrupted courses of the wall without very material alteration. I avoid this to a large extent. In Figs. 1, 2 and 3 I have shown the falsework for a window opening. A window frame is indicated at 20 supported at its bottom by timbers 21. A series of beveled strips 22 is temporarily fastened to the window frame at an angle to the plane of the frame and the vertically 95 25

fastened to the window frame at an angle to the plane of the frame and the vertically 100

arranged strips on the inside and outside of the frame are additionally supported by clamping arms 23 which are held in position by a horizontally disposed jack 24. The 5 window frame is usually slightly greater in width than the hollow space formed in the wall, and as shown herein the beveled strips 22 extend from the window casing outwardly to the members 1 of both the sets 10 A and B and their inclination is such that the concrete poured into the spaces between the members 1 and 2 of each set A and B will have a beveled formation at the window when the beveled strips 22 are removed, thus 15 avoiding the necessity of applying a finishing casing on the inside or outside. As shown in Fig. 1 the boards of the outer members of the set B are provided with metal plates 25 similar to those used with the 20 boards 12. These plates aid in securing a flush fit against the beveled strips 22 at the inside of the window. Additional plates 26 are secured to some of the boards and act as keepers for extra boards 27. By this 25 arrangement an opening of great width can readily be taken care of.

The parts of my improved mold are readily assembled as will be apparent from the description of each of the parts. With the 30 members properly arranged concrete is poured between the inner and outer members of each set A and B and allowed to harden. Thereafter the bolts 5 are unscrewed from the plates 6, the strips 7 carrying the plates being lifted from the hollow of the wall. The inner mold members may then be taken out and the outer boards 1 removed. Access may then be had to the 35 beveled strips 22 temporarily secured to the window frame, or if it be desired these strips may be allowed to remain in place so as to protect the edges of the concrete until all likelihood of damage to these edges in the building operations is removed. Dislodgment 40 of these strips is an easy matter. As before stated the concrete about the window is provided with a beveled face thus obviating the necessity of finishing casings. The strips 7 are shown in Fig. 4 in vertical arrangement solely for clearness in illustration. In practice they are placed horizontally.

I claim as my invention:

1. In the construction of hollow concrete 5 walls, a form including inner and outer spaced sets of spaced apart members, means for maintaining the outer members of each set in side to side alinement, spacing blocks between the outer and inner members of 60 each set, and a locking element within the space which will form the hollow of the wall adapted to coöperate with the means for maintaining the outer members in alinement, complementary locking elements of

the inner and outer sets being arranged face 65 to face to form spacing means between the inner and outer sets.

2. In the construction of hollow concrete walls, a form including inner and outer spaced sets of spaced apart members, means 70 for maintaining the outer members of each set in side to side alinement, spacing blocks between the outer and inner members of each set, rods extending transversely through said spaced apart members, and a locking 75 element within the space which will form the hollow of the wall adapted to coöperate with the means for maintaining the outer members in alinement comprising strips arranged end to end and each having a screw 80 threaded portion for engagement with said transverse rods, complementary locking strips of the inner and outer sets being arranged face to face to form spacing means between the inner and outer sets. 85

3. In the construction of hollow concrete walls, a form including inner and outer spaced sets of spaced apart upright boards, means for maintaining the outer boards of each set in side to side alinement, spacing 90 blocks for separating the boards of each set, plates on some of said boards and extending beyond the sides thereof in overlapping engagement with the next adjacent and alined board, said plates having openings therein, 95 rods extending transversely of said spaced apart boards and through the openings of said plates, one end of said rods being screw threaded, and locking elements within the space which will form the hollow of 100 the wall comprising strips arranged to interlock end to end and each having a screw threaded portion for engagement with said transverse rods, complementary locking strips of the inner and outer space being arranged face to face to form spacing means between the inner and outer sets. 105

4. In the construction of hollow concrete walls with openings for doors and windows, a form including inner and outer spaced 110 sets of spaced apart boards, means for maintaining the outer boards of each set in side to side alinement, spacing blocks between the outer and inner boards of each set, a locking element in part within the space 115 which will form the hollow of the wall, a frame supported between the outer boards of each set, strips having their side edges beveled, such strips being temporarily secured to said frame at an angle to the planes 120 thereof to cause one beveled edge to lie flush against the inner face of said outer board.

5. In the construction of hollow concrete walls with openings for doors and windows, a form including inner and outer spaced sets 125 of spaced apart boards, means for maintaining the outer boards of each set in side to side alinement, spacing blocks between the

outer and inner boards of each set, a locking element in part within the space which will form the hollow of the wall, a frame supported between the outer boards of each set, 5 strips having their side edges beveled, such strips being temporarily secured to said frame at an angle to the planes thereof to cause one beveled edge to lie flush against the inner face of said outer board and clamping elements for maintaining said 10 beveled strips in position on said frame.

In testimony whereof I have signed this specification.

BENJAMIN FARNESS.
